A. A. LOW.

ELECTRICALLY OPERATED STARTING VAPORIZER FOR COMBUSTION ENGINES.

APPLICATION FILED JUNE 8, 1907. RENEWED DEC. 1, 1908.

909,917.

Patented Jan. 19, 1909.

UNITED STATES PATENT OFFICE.

ABBOT A. LOW, OF HORSESHOE, NEW YORK.

ELECTRICALLY-OPERATED STARTING-VAPORIZER FOR COMBUSTION-ENGINES.

No. 908,917.

Specification of Letters Patent.

Patented Jan. 19, 1900.

Application filed June 8, 1907, Serial No. 377,849. Renewed December 1, 1903. Serial No. 465,580.

To all whom it may concern:

Be it known that I, ABBOT AUGUSTUS LOW, a citizen of the United States, residing in Horseshoe, in the county of St. Lawrence 5 and State of New York, have invented a certain new and useful Electrically-Operated Starting-Vaporizer for Combustion-Engines, of which the following is a specification.

This invention is a vaporizer for internal 10 combustion engines, said vaporizer being intended, more particularly, for producing a combustible vapor for starting the engine.

Certain types of internal combustion engines require, in their operation, two kinds 15 of fuel, one of a readily volatile character, such as gasolene for starting the engine, and the other, of a less volatile character, such as kerosene, for maintaining it in operation.

It has been proposed to supply kerosene 20 to an engine for running it, but, in practice, great difficulty has been experienced in starting the engine quickly with a fuel so unvolatile, and, for this reason, gasolene is resorted to for initially putting the engine into operation, after which the gasolene feed is discontinued and kerosene supplied for continuing the operation of said engine. It has been observed, furthermore, that when kerosene is thrown against a heated surface, a 25 certain quantity of it is not vaporized, the surplus liquid running into the lower part of the vaporizing chamber.

The present invention permits the employment of kerosene for both starting and running the engine, and is particularly efficacious in producing a complete volatilization 30 of the kerosene, although it will be understood that the device is applicable for use with the more volatile fluids, such as gasolene 35 or alcohol.

The object of the invention is to quickly heat a starting vaporizer, and to collect the liquid fuel which is not converted into vapor by the first contact thereof with a hot surface, the liquid so collected being free to spread or diffuse itself over a comparatively 45 large area, preferably heated, placed in the path of the air or vapor which is to be admitted to the combustion cylinder.

50 My vaporizer is heated electrically in

order to place it in condition for service quickly, and as heretofore stated, said vaporizer enables one kind of a comparatively unvolatile fuel, such as kerosene, to be used for starting and operating the engine.

55

In the accompanying drawings, I have illustrated one practical embodiment of the invention, but the construction shown therein is to be understood as illustrative only, and not as defining the limits of the invention.

60

Figure 1 is a vertical longitudinal section through a vaporizer embodying my invention and shown in operative relation to a part of a combustion chamber. Fig. 2 is a horizontal section on the line 2—2 of Fig. 1.

The engine cylinder, A, is shown in Fig. 1 as having a piston chamber, a, and a cooling chamber, a', the latter being adapted for the circulation of a cooling agent, such as water, around the piston chamber, a.

70

Charges of combustible vapor are admitted to the chamber, a, by the opening movement of an intake valve, C, and such charges of vapor are adapted to be exploded in said chamber, a, by the operation of the igniter 75 or spark plug, D.

The valve, C, is supplied with the charges of combustible vapor through an intake port, e, which is provided in a head, B, the latter being secured by bolts, b, to the cylinder, A, 80 said head, B, having a circulating chamber, b', for a cooling medium. To the head, B, is secured an elbow, E, which is provided with a guide boss, e, and through this boss passes the stem, d, of the intake valve, C.

85

This valve stem is provided with a collar, d', on which acts a coiled spring, d', whereby the valve is adapted to be closed normally on its seat, e'. The valve, C, is operated positively by suitable mechanical connections 90 with a moving part of the engine, and as one means for operating said intake valve, I have shown a lever, E'. Said lever is provided at one end with an adjusting screw, e', adapted for engagement with the valve rod, d, and the other end of said lever is equipped with another adjusting screw, f, with which engages a reciprocating rod, F, the latter being operated by the engine. As shown in Fig. 1, the elbow, E, is provided with a 100

95

bracket lug, e^2 , in which is supported a fulcrum pin, e^3 , of the valve operating lever, E' .

The parts hereinbefore described are common in this art, and no novelty therefor is claimed herein.

The working parts of my new vaporizer are contained within a box or casing, G , which is flanged and bolted, or otherwise united, to the intake end of the elbow, E .
 10 This box or casing may be of any suitable form and size so as to produce a chamber, g , of the desired capacity for mixing air and vapor to produce the combustible charges adapted to be admitted to the engine cylinder.
 15 It is preferred to provide the box or casing, G , with a chamber, g' , into which the exhaust from the engine is admitted by suitable circulating pipes, r , whereby the waste heat and gases may be utilized for heating
 20 the vaporizer when the engine is in operation. The box or casing, G , is shown as having a lip or flange, h , which provides an air inlet, h' , to the chamber, g , and the volume of air admitted through said inlet is adapted
 25 to be regulated by a pivoted valve or regulator, H , the latter being shown as having a handle, h^2 , for its convenient operation. The box or casing, G , is open at the end opposite to its connection with the elbow, E ,
 30 and this open end is closed by a head, I , the latter being flanged and bolted to the box or casing, G , so as to close the open end thereof, and to close one end of the circulating chamber, g' . Said head, I , is provided with an extension, I' , which is preferably integral
 35 with the head, and it projects inwardly therefrom into the lower part of the chamber, g . The extension, I' , is quite close to the bottom of the vaporizing box or casing,
 40 G , and said head, I , with its extension, I' , forms the support for the parts of the electrical vaporizer to be presently described.

The head, I , is provided, preferably, with an internally threaded boss, i , which constitutes a socket for the reception of the male threaded plug, J . This plug is adapted to be screwed detachably to the vaporizer, and as is usual in electrical connections, said plug is provided with a conducting cord or
 45 wire, j , and with a contact, j' .

My new vaporizer contemplates the employment of a vaporizing element composed of the members, K , K' , the same being preferably made in one piece and composed of
 50 a metal adapted to be quickly heated by an electrical current, such for example as copper. The members, K , K' , of the vaporizing element are arranged at right angles to each other, and they are placed in co-operative relation to the head, I , and its extension or shelf, I' . It is preferred to place the member, K , in a vertical position and opposite to the head, I , whereas the member, K' , is opposite to the shelf or extension, I' .

The member, K' , is provided on its upper 65 surface with ribs, corrugations or otherwise constructed to increase the area of the heating surface for the liquid which may collect thereon. As shown more clearly in Fig. 2, the upper surface, k , of the member, K' , 70 is provided with intersecting grooves or channels, k' , which give the desired corrugations to such surface, thus increasing the area of the member, K' , over which the liquid is free to spread or diffuse itself. Any 75 suitable means may be employed for clamping the vaporizing element to the head, I , and its shelf or extension, I' , but, as shown, I employ screws, m . The member, K' , is provided with a marginal lip or flange, k^2 , 80 adapted to form a drain gutter around the edge of said member, and from this member leads a drain pipe, l , having a draw-off valve, l' , whereby surplus liquid may be discharged from the member, K .
 85

I employ means for electrically heating the vaporizing element. Said electrical heating means may be arranged to co-operate with the member, K , or with the member, K' , but it is preferred to employ an electrical heater which engages both of the members for the purpose of quickly heating the vaporizing element to the temperature required for converting kerosene into a combustible vapor adapted for admixture with 90 air.

Various forms of electrical heating devices may be employed, but as shown in Fig. 1, the heating means consists of a resistance wire or ribbon, O , which is doubled or folded 100 around a core, p , of insulating material, such as mica. The resistance wire or ribbon and its core are arranged between the member, K , and the head, I , and they are extended between the member, K' , and its shelf, I' , 105 as clearly shown in Fig. 1. Resistance O is insulated from electrical contact with the members, K , K' , by an insulating layer, q , and said resistance is likewise insulated from electrical contact with the head, I , and its extension, I' , by an insulating layer, q^2 . One end of the electrical resistance is adapted for electrical connection with the contact, j' , of the plug, J , but the return lead, o , of said electrical resistance, O , is extended between layers, q' , q^2 , 110 of insulating material. Said layers of insulating material, q , q' , q^2 , are composed preferably of mica.
 115

The electrical resistance is clamped between the parts, I , I' , and the members of the vaporizing element whereby the heat developed in the resistance by the passage of an electrical current therethrough is adapted to be transmitted to and absorbed by the 120 parts, K , K' .
 125

One means for supplying a combustible liquid to the vaporizer consists of a jet noz-

zle, G', which is attached to the elbow, E. The liquid combustible is supplied under pressure to the nozzle, G', preferably by the operation of a suitable pump. The jet of liquid is forced under pressure across the elbow, E, and the box or casing, G, so as to strike against the member, K, of the vaporizing element, thereby converting the liquid into vapor. A portion of this liquid, however, is not vaporized, and it rebounds from or is deflected by the member, K, upon the other member, K'. The liquid which accumulates on said member, K', diffuses itself over the corrugated surface, k, whereby the liquid on the member, K', is heated by the resistance which extends between the parts, K', I'. The liquid combustible is fully vaporized, and it is combined with air so as to produce the combustible charge adapted to be admitted to the chamber, a, of the cylinder when the valve, C, is open, in the manner well understood by those skilled in the art.

Having thus fully described my invention, what I claim as new and desire to secure by Letters Patent, is:—

1. In a device of the class described, a vaporizing element composed of heat-absorbing metal of high conductivity, and having two surfaces at an angle to each other, one of said surfaces being corrugated to increase its surface area, and electrical means for directly heating said element.

2. In a device of the class described, a vaporizing element composed of heat-absorbing metal of high conductivity and comprising two members, one of which is adapted to collect surplus hydrocarbon discharged against said other member, and electrical means for directly heating said element.

3. In a device of the class described, a vaporizing element composed of two members, at an angle to each other, one of said members being adapted to collect surplus hydrocarbon discharged against said other member, means for bringing a hydrocarbon into contact with the said other member, and means for heating the element.

4. In a device of the class described, a vaporizing element composed of an upright member and a collecting corrugated member at an angle to the upright member, said collecting member being substantially continuous with the upright member and arranged for its corrugated surface to collect surplus hydrocarbon which is discharged from said upright member.

5. In a device of the class described, a vaporizing element composed of an upright member and a collecting member at an angle to the upright member, said collecting member having a grooved diffusing surface, said collecting member being substantially continuous with the upright member and ar-

ranged for its corrugated surface to collect surplus hydrocarbon which is discharged from said upright member.

6. In a device of the class described, a metallic vaporizing element comprising an upright member, a collecting member having a grooved or corrugated surface over which a hydrocarbon is free to spread, and electrical means for directly heating the metal composing both members of said element.

7. In a device of the class described, an electrically heated vaporizing surface, means for collecting the surplus fuel discharged against or supplied to said surface, and electrically heated means coöperating with said collecting means for vaporizing the surplus fuel collected thereby.

8. In a device of the class described, a chamber having means for admitting air thereto, a vaporizing element in said chamber, said element consisting of a plurality of heat-absorbing metallic members, one of which is adapted to collect a liquid, an electrical resistance in coöperative relation to said members of the vaporizing element, whereby said element is electrically heated by the direct application of a heating resistance thereto, and means for projecting a liquid against one of said members of the element.

9. In a device of the class described, a chamber having means for admitting air thereto, a vaporizing element in said chamber and composed of metallic heat-absorbing members at an angle to each other, one of which is adapted to collect a liquid, means for draining surplus liquid from said collecting member, an electrical resistance coöperating with both of said members, and means for projecting a liquid combustible against the other member of the vaporizing element.

10. In a device of the class described, a chamber having means for admitting air thereto, a vaporizing element in said chamber, said element consisting of two members at an angle to each other, one of said members extending outwardly into the chamber and is adapted to collect a liquid discharged from the other member, and an electrical resistance coöperating with both members of said vaporizing element.

11. In a device of the class described, a chambered casing or box, a head closing said box and having an inwardly extending shelf, an angular vaporizing element coöperating with the head and the shelf thereon, and an insulated electrical resistance clamped between the vaporizing element and the head and its shelf.

12. In a device of the class described, a chambered casing or box, a head closing said box and having an inwardly extending shelf, a connecting plug attached to said head, an

angular vaporizing element, and an electrical resistance connected electrically with the plug and confined between the vaporizing element and the head and its shelf.

13. In a device of the class described, a box or casing, a collecting vaporizing element therein and comprising two members at an angle to each other, one member being provided with a drain gutter and with a

corrugated surface, and means for electrically heating both members of said element.

In testimony whereof I have signed my name to this specification in the presence of two subscribing witnesses.

ABBOT A. LOW.
